(57) **CLAIM**

The ornamental design for a window component extrusion, as shown and described.

DESCRIPTION

FIG. 1 is a rear perspective view of a window component extrusion showing our new design.

FIG. 2 is a rear elevation view thereof.

FIG. 3 is a front elevation view thereof.

FIG. 4 is a left side elevation view thereof, for which a right side elevation view (not shown) is a mirror image; and, FIG. 5 is a bottom plan view thereof, for which a top plan view (not shown) is a mirror image.

In FIGS. 1-3 and 5, the window component extrusion is shown with a symbolic break in its length. The broken lines at the symbolic break form no part of the claimed design. The appearance of any portion of the window component extrusion between the break lines forms no part of the claimed design.
